UNITED STATES PATENT OFFICE

SYLVARIUS A. SPRINKLE, OF MARTINSBURG, WEST VIRGINIA

RAIL JOINT

Application filed February 5, 1932. Serial No. 591,179.

My present invention has reference to a new and novel means for connecting the meeting ends of railway rails, and among my objects is the provision of means which firmly hold the rail ends connected, permit of the rails expanding and contracting under weather conditions, hold the rail from creeping, which permits of the longitudinal movement of one of the rails independent of such movement of the other rail, should one of the rails expand or contract to a greater degree than the other rail and which also establishes an effective electric bond between the rails.

15 A further object is to simplify and improve the rail joint constructions upon which I have received U. S. Letters Patent No. 1,839,058, granted on December 29, 1931, and No. 1,850,900, granted on March 22, 1932.

20 To the attainment of the foregoing the invention consists in the improvement herein-after described and definitely claimed.

In the drawings:

Figure 1 is a side elevation of the ends of 25 two rails jointed in accordance with this invention.

Figure 2 is a top plan view thereof.

Figure 3 is an end view of the joint with one of the rails in section.

30 Figure 4 is a sectional view on the line 4—4 of Figure 1.

Figure 5 is a horizontal sectional view on the line 5—5 of Figure 1.

Figure 6 is a perspective view of one of the 35 chair members.

Figure 7 is a perspective view of one of the body members.

Figure 8 is a perspective view of one of the 40 combined rail anti-creeping and bond members.

As disclosed by the drawings my improved joint is arranged between and has its ends, at the lower portion thereof, in contacting engagement with the confronting sides of ties 45 1 upon which the ends of railway rails 2 rest and are spiked.

The improvement contemplates the employment of two similarly constructed rail chairs 3, respectively. The chairs are of a 50 length equaling the distance between the ties

1 and the inner face of each chair is inwardly cut and grooved longitudinally the entire length of the chair to define a lower flat wall 4 and an overlying angle wall 5, and between which walls the base flanges of the rails 2 are 55 received. The confronting faces of the chairs 3, above the rail flange receiving grooves or pockets have other but inwardly curved grooves 6 and the outer faces of the chairs opposite the grooves 6 are reduced in 60 width by beveling or cutting such faces angularly, as indicated by the numeral 7. The upper edge of each chair 3 is inclined, as at 8, to underlie the head of the rails at the opposite side of the web of such rails. From 65 their confronting ends the flat bottom portions of the chairs are formed with downwardly extensions or plates 9, and these plates have their lower ends, at their inner faces, flanged, as at 10, and the straight ends or 70 faces of the flanges are designed to contact with each other when the chair members are associated to grip rail ends therebetween.

The chair members are received in a metal substantially U-shaped body. The body comprises two similar right angular members whose outer and upwardly directed flanges are indicated for distinction by the numerals 11 and whose lower or base flanges are indicated by the numerals 12. The confronting edges of the flanges 12 are designed to abut, and there is arranged between the lower ends of the plates 9 on the chair members a sheet 13 of insulating material. Sheets 14 of like 75 insulating material are arranged between the lower straight outer sides of the chair members and the inner faces of the upstanding parts 11 of the substantially U-shaped body. There is also preferably arranged between the confronting ends of the rails 2 a filler 80 strip 15 which is shaped to correspond with the cross sectional contour of the rails. The rails and chair members are insulated from the channelled or U-shaped body.

The webs, at the ends of the rails received between the chairs are each provided with a round opening, and these openings 16 are preferably slightly tapered from the opposite sides of the respective webs. Before the joint 85 is assembled I wedge in each of the openings 100

16 the preferably slightly tapered inner offset end 17 of brass or like metal rods 18 which have a high electric conductivity. The rods are received in the grooves 6 in the respective 5 chair members, and are extended in opposite directions through said grooves. The outer ends of the rods 18 are offset or formed with oppositely extending lug portions 19 disposed in close proximity to but out of contact with 10 the diagonally opposed ends of the respective chair members. The joint is now assembled as heretofore described and the joint members are held associated by bolts 20 whose stems pass through alining openings 21—21 in the 15 depending portions or plates 9 and openings 22—22 in the vertical flanges or sides of the channeled or U-shaped body. The bolts 20 are arranged below the base portions proper of the chair members and are contacted by 20 the lower edges of the insulating strips 14. In the openings 21—21 of the depending flanges 10 of the chair members there are sleeves 50 of insulating material through which the bolts 20 pass and which sleeves 50, 25 together with the strips 14, insulate the base 12 from the remainder of the joint. The bolts have screwed on their outer ends nuts 23, and when the nuts are screwed home the sides 11 of the channeled or U-shaped body 30 will be compressed toward each other and thus forced toward the lower and straight side of the chair members 3. Such compression of the chair members tends to cause the outer and reduced portions 24 of the chairs to 35 expand in an outward vertical direction, causing the edges 18 of the said chair members to be forced both upwardly and inwardly with respect to the fishing spaces in the rails to bring all of the rail engaging portions of 40 the chairs into tight frictional engagement with the rails and effectively sustain the tread portion of the heads of the rails in positive alinement so that the sinking of the rail ends, 45 incident to the weight of the rolling stock passing thereover will be effectively obviated. The outer faces of the offset ends 17 of the respective bond and anti-creeping rods 18 are at all times in contact with the inner faces of the respective rods 18, thus establishing 50 a perfect electrical connection between the rails. The outer offset ends 19 of the rods 18 being arranged opposite and in close proximity to the diagonally opposed ends of the respective chair members will 55 prevent the creeping of the rails, permit of the expansion and contraction of said rails and allow one of the rails expanding or contracting to a greater degree than the other rail. 60 It is believed that the construction and advantages of my improvement will be understood and appreciated by those skilled in the art to which the invention relates when the foregoing description has been read in connection with the accompanying drawings. It 65

is, of course, to be understood that the roadbed is tamped beneath the channeled body of the joint as well as along the sides thereof. The joint is thus held from downward movement and is prevented from longitudinal movement by contact with the ties 1, which ties are also suitably tamped in the roadbed. Changes in minor details of construction, 70 not interfering with the scope of the invention as expressed in the appended claims may be resorted to. 75

Having described the invention, I claim:

1. In a rail joint, two rail chairs, on which the base flanges of the confronting ends of two rails rest and in whose fishing spaces the chairs are received, said chairs having their confronting faces grooved, longitudinal rod members secured to the webs of the rails extending in opposite directions through the respective grooves, and having offset ends disposed opposite but slightly out of contact with the diagonally opposed ends of the respective chairs, together with means for binding the chairs against the rails. 80

2. In a rail joint, two rail chairs, on which the base flanges of the confronting ends of two rails rest and in whose fishing spaces the chairs are received, said chairs having their confronting faces grooved, rods of electric conductivity having inner offset ends that are passed through the webs of the respective rails, said rods being oppositely directed, so that the offset end of one of the rods will contact with the body of the other rod, and the outer ends of the rods being offset in opposite directions and directed toward but disposed a slight distance from the diagonally opposed ends of the rail chairs, the confronting ends of the rails having an insulating strip therebetween, and means for forcing the chairs toward each other into frictional contact with the base flanges and the heads of the rails. 100

3. In a rail joint, two rail chairs, on which the base flanges of the confronting ends of two rails rest and in whose fishing spaces the chairs are received, said chairs having their confronting faces grooved, rods of electric conductivity having inner offset ends that are passed through the webs of the respective rails, said rods being oppositely directed, so that the offset end of one of the rods will contact with the body of the other rod, and the outer ends of the rods being offset in opposite directions and directed toward but disposed at a slight distance from the diagonally opposed ends of the rail chairs, the confronting ends of the rails having an insulating strip therebetween, a twopart channeled body in which the lower portion of the rails is received, means insulating the body from the chairs and adjustable means passing through the sides of the body for compressing said sides and for likewise compressing the chair members to impart a vertical and lateral ex- 115 120 125 130

pansion to the upper portion thereof for forcing said portions into tight frictional engagement with the rails.

4. In a rail joint, two rails resting on ties, 5 chair members for the rails disposed between and contacting the confronting sides of the ties, means for compressing the chair members against the rail ends, and means fixed on the web of each of the rails extending 10 outwardly therefrom and having angle ends disposed opposite but slightly out of contact with the ends of the respective chair members.

5. A rail joint including rail ends resting 15 on the ties, cooperating chair members affording a rest for the rail ends and disposed between the ties and in contact therewith, a two-part channeled body receiving the chair members therein, said rail ends being insulated from each other and said chair members being insulated from the body, means 20 comprising bolts and nuts for forcing the body sections toward each other to compress the chair members against the rails, and 25 means carried by the webs of the rails extending at opposite directions therefrom through the chair members and having angle ends spaced slightly from but in the path of contact with the respective chair members.

30 6. In a rail joint, two rail ends, a pair of chair members affording rests for the rails and contacting with the under face of the heads of the rails, said chair members having their confronting faces grooved longitudinally throughout the length thereof, rods 35 of electric conductivity having offset ends which wedgingly pass through openings from the opposite sides of the webs of the respective rails and which extend in opposite 40 directions through the grooves in the chair members, said rods having their outer ends offset and disposed opposite but slightly out of contact with the respective chair members and means for forcing the chair members 45 toward each other and for holding the same in such condition to cause the chair members to tightly engage with the rails and to likewise cause the ends of the inner offset portions of each rod to contact with the body 50 portion of the adjacent rod.

7. A rail joint including two rail ends, a pair of chair members affording a rest for the rails, laterally extending means carried by the webs of the rails slightly spaced from 55 the ends of the respective chair members, a channeled body on which the chairs rest and bolt members engaged by nuts passing through the sides of the body below the rails and the base portions of the chairs for compressing the sides of the body against the sides of the chairs, to compress and to expand the upper portions of the chairs toward and against the rails.

In testimony whereof I affix my signature.
C3 SYLVARIUS A. SPRINKLE.
